UNITED STATES PATENT OFFICE.

ARTHUR D. HAMLIN, DECEASED, LATE OF PORTLAND, MAINE; BY MINNIE M. HAMLIN, ADMINISTRATRIX, OF PORTLAND, MAINE.

SHAKING AND DUMPING GRATE.

Refiled for abandoned application Serial No. 293,806, filed December 29, 1905. This application filed September 11, 1924. Serial No. 737,443.

To all whom it may concern:

Be it known that ARTHUR D. HAMLIN, late a citizen of the United States, deceased, residing at Portland, in the county of Cumberland and State of Maine, did invent new and useful Improvements in Shaking and Dumping Grates, of which the following is a specification.

This invention relates to an improvement in shaking and dumping grates and more particularly to grates of this character employing rocking bars.

The object of this invention is the provision of a grate of this character in which the rocking bars are so formed and assembled that coals and clinkers will be prevented from accumulating between the ends thereof during the shaking movement thereof and thereby clogging the grate.

20 A further object of the invention is the provision in a grate of this character of means for maintaining the air space during the shaking movement of the grate as when in its normal position.

25 A still further object of the invention is the provision of improved means for rocking the grate bars, whereby they may be rocked further on their axes than has heretofore been practical, to completely effect 30 the dumping of the fire.

Other objects of the invention will be apparent from the detailed description hereinafter, when read in connection with the accompanying drawings, wherein a 35 preferable embodiment of my invention is shown and wherein like numerals of reference refer to similar parts in the several views.

In the drawings, 40 Figure 1 is a fragmentary perspective view of a furnace clip with my improved grate,

Fig. 2 is a transverse section through the grate frame.

45 Fig. 3 is a cross-section showing several of the grate bars in their shaking position,

Fig. 4 is a longitudinal section showing the grate bars in their normal position, and

50 Fig. 5 is a longitudinal section, with parts in elevation, showing the grates in their dumping position.

Referring now more particularly to the drawings, A designates the frame of my improved grate, which is preferably rec-

tangular in form and comprises the end 55 pieces B and the side pieces C, which are adapted to be supported in any suitable manner within the furnace. The end pieces B of the grate frame are provided with the inwardly extending spaced arms or teeth b, 60 for a purpose to be hereinafter set forth. The side pieces C are provided with the inwardly extending lugs c, which have their upper surfaces curved to form the pivotal supports for the rocking bars D. The rocking bars D each comprises a central portion d, in the ends of which are formed the seats or pockets d', which are adapted to be supported by and to have a rocking movement upon the lugs c, which are formed on 65 the inner sides of the side pieces C of the grate frame, and the spaced arms or teeth d'', which extend laterally from each side thereof. The teeth at each side of the grate bars are arranged in staggered relation so 70 that when said bars are secured in position within the grate frame A, the teeth of each bar will extend into and substantially fill the space between two of the teeth of the next adjacent bar, the outer rows of teeth 75 on the end grate bars extending into the spaces between the arms or teeth b projecting from the end pieces B of the grate frame. When the grate bars D are in their assembled position, the ends of the teeth 80 d'', of each bar extend into proximity to the central portion d of the next adjacent bar. The ends of said teeth are curved substantially on the arc of a circle, the center 85 of which is the pivotal point of the rocking bars, as at d', so that they will maintain the same relative position with reference to said central portion d during a portion of their rocking movement. In other words, 90 the distance between the ends of the teeth d'' and the central portion d of the adjacent rocking bar will remain constant until the rocking bar is moved a sufficient amount to permit the ends of the teeth to completely clear said central portion. Each 100 of the grate bars D has projecting downwardly from the central portion d thereof, an arm d⁴ which is provided at its free end with a bifurcated portion d⁵. The arm d⁴ of each grate bar is positioned directly in 105 rear of one of the teeth d'' thereof and is of such a thickness that when the grate bar is moved to its dumping position, the said

arm may move up into the space formerly occupied by said tooth between two of the teeth of the next adjacent bar. E designates a rod which extends transversely of the grate bars D and is provided with a plurality of upwardly extending arms e, which extend into the bifurcated portions d⁵ of the depending arms d⁴ of the grate bars and are pivotally secured therein in any suitable manner. The forward end of the rod E is pivotally connected by a link F, which projects through the front of the furnace, to the lower end of an actuating lever G which is pivotally secured to a bracket H attached to the front of the furnace.

The end pieces B of the grate frame and the central portion d of the rocking bars D are provided with air apertures extending therethrough.

Having described the construction of my improved grate, I will now set forth the manner of using the same.

When it is desired to shake the fire, the operating lever G is moved to rock the grate bars D to a limited extent only, so that the ends of the teeth d'' thereof will not clear the central portion d of the next adjacent bar, and as the ends of said teeth are curved so that the same distance will always be maintained between the ends thereof and the central portion d of the next bar, it will be seen that no clinkers can accumulate between the ends of the teeth and the central portions d and thereby interfere with the rocking movement of the bars. Furthermore, as the ends of the teeth always remain the same distance from the central portion of the next adjacent bar during the shaking movement of the bars, it will be apparent that the same air space will be maintained during the shaking movement of the grate as when in its normal position. When it is desired to dump the fire, the actuating lever G is moved to cause

the teeth of each grate bar to clear the teeth of the next adjacent grate bar. Owing to the positioning of the depending arms d'' and the connection of the rod E therewith by means of upwardly extending arms e, it will be apparent that the grate bars can be turned to a position at substantially right angles to the grate frame to completely effect the dumping of the fire.

I do not desire to limit myself to the precise form and construction shown in the drawings, as it is obvious that many minor changes might be made thereto without departing from the spirit of the invention.

What I desire to secure by Letters Patent is:—

A grate of the character described comprising a frame, a plurality of toothed grate bars journaled therein, the teeth of each of said bars being arranged to occupy the space between the teeth of the next adjacent bar, an arm depending from the central portion of each of said rocking bars, said arm being positioned directly in rear of one of the teeth of said bar and of less width than the space between adjoining teeth on the next adjacent bar and being of a length to permit its entrance into said space and to clear the adjacent bar when the bars are rocked, a bar extending transversely of said grate bars and provided with a plurality of upwardly extending arms directly underlying and pivotally connected to the free ends of the arms depending from said grate bars, and means for imparting a reciprocatory movement to said bars.

In testimony whereof I hereunto affix my signature in the presence of two witnesses.

MINNIE M. HAMLIN,
Adm^x. estate of Arthur D. Hamlin, deceased.
